UNITED STATES PATENT OFFICE.

JOHN F. O'CONNOR, OF CHICAGO, ILLINOIS, ASSIGNOR TO WILLIAM H. MINER, OF CHICAGO, ILLINOIS.

DRAFT-RIGGING FOR RAILWAY-CARS.

1,152,039.

Specification of Letters Patent. Patented Aug. 31, 1915.

Application filed May 22, 1912. Serial No. 698,890.

To all whom it may concern:

Be it known that I, JOHN F. O'CONNOR, a citizen of the United States, residing at Chicago, in the county of Cook and State of Illinois, have invented a certain new and useful Improvement in Draft-Rigging for Railway-Cars, of which the following is a full, clear, concise, and exact description, reference being had to the accompanying 5 drawings, forming a part of this specification.

My invention relates to improvements in draft rigging for railway cars.

The object of my invention is to provide 15 a draft rigging in which the shock absorbing member and the draw bar are connected by a simple, strong and efficient means, and one of durable and cheap construction.

In the accompanying drawings forming 20 a part of this specification Figure 1 is a side elevation partly in longitudinal section of a draft rigging embodying my invention. Fig. 2 is a plan view of the same. Fig. 3 is an enlarged detailed view showing in elevation partly in vertical longitudinal section 25 my improved means of connecting the shock absorbing member with the draw bar. Fig. 4 is a rear end view at line 4—4 of Fig. 3. Fig. 5 is an enlarged detail plan 30 view partly in horizontal section of my improved means of connecting the shock absorbing member with the draw bar shown partly in horizontal section. Fig. 6 is a cross sectional view on line 6—6 of Fig. 3. Fig. 7 is an enlarged front end view of the 35 shell. Fig. 8 is an enlarged side elevation of the shell, and Fig. 9 an enlarged plan view of the shell.

In the accompanying drawings 10, 10 represent 40 the center sills of a railway car, or that part of the car frame to which the draft rigging is attached; 11 the end sill, 12 the buffer block; 13 the draw bar carry iron; 14, 14 the front stop castings provided with 45 the stop shoulders 15, 15; 16, 16 the rear stop castings provided with the stop shoulders 17, 17; 18 the intermediate stop castings provided with the front and rear limiting stop shoulders 19, 19 and 20, 20 respectively.

21 is the draw bar of the usual type provided with the transverse slot 22 for the passage of the coupler key 23.

24 is the shock absorbing member comprising 55 the shell 25 and its contained com-

pression resisting parts, which may be of any suitable type.

26 is the front and 27 the rear tie plate bolted to the center sills 10, and each of a suitable width to support the shell 25 in its 60 reciprocating movements between the center sills.

28 is the front follower and 29 the rear follower, which is integral with the shell 25.

30 is the means of connecting the shell to 65 the draw bar, and is provided at its forward end with a box like opening 31 to receive the rear end of the draw bar 21. At either side of the opening 31 the lateral plates 32, 32 are preferably forwardly extended, forming 70 the wings 33, 33. The plates 32, 32 are provided with the slots 34, 34 in alinement with the slot 32 in the draw bar, through which slots the coupler key 23 is passed. I prefer to also provide the adjacent stop members 75 14, 14 and the adjacent portions of the center sills 10, 10 with horizontal slots registering with the slots 34, 34 so that the coupler key may be extended through them, and inserted and removed from without the center sills. 80 The top and bottom plates 35 and 36 respectively of the member 30 are rearwardly extended, as illustrated in Fig. 3 of the drawings, and are connected at their rear ends by the transversely arranged annular 85 band 37. In front of the annular band 37 and on the inner or lower side of the plate 35 is provided a lug 38. A similar lug 39 is provided on the inner or upper surface of the lower plate 36. 90

The friction shell 25, which is preferably a hollow cylinder in shape or circular in cross section open at its forward and closed at its rear end, is externally provided near its forward end with an annular band 40, and at its forward end at top and bottom with the projecting lugs 41 and 42. The band 40 and the lugs 41 and 42 are suitably separated to form the ways or slots 43 and 44 respectively, which receive the lugs 38 and 39 respectively of the member 30, and the band 37 of the member 30 encircles the band 40 of the cylinder 25. In attaching the member 30 to the shell 25 the said member 30 is held with the sides 31, 32 in a horizontal 100 plane. The member 30 is then slipped upon the shell, the lugs 38 and 39 of the member 30 being of suitable length to permit their passage through the spaces 45 and 46 between the lugs 41 and 42 upon the shell 25. 110

The lugs 41 and 42 are of suitable length to pass through the spaces 47 and 48 between the lugs 38 and 39 of the member 30. The member 30 is then given a quarter turn, 5 bringing the lugs 38 and 39 within the slots 43 and 44, thus securing the member 30 to the shell 25. The member 30 is prevented from turning from its attached position by the front follower 28, which is passed 10 through the transverse opening 49 in the member 30. The opening 49 is of suitable longitudinal dimension to permit the insertion and removal through the open forward end of the shell of its contained compression 15 resisting parts.

In preferable construction the slots or ways 43 and 44 provided in the friction shell are inwardly tapered from the periphery of the shell; and the lugs 38 and 39 of the member 30 are outwardly tapered from the inner surface of the plates 35 and 36 so that the lugs 38 and 39 dovetail with the slots 43 and 44. I prefer to core out the rear follower 29, as illustrated in Fig. 8 of the drawings, 25 and to reinforce the shell, as illustrated at numeral 50.

I claim:

- 1. In a device of the character described, a shell to contain the compression resisting parts, a draw-bar, and a member connecting the draw-bar and shell, the shell being provided with external lugs and an annular band spaced from said lugs forming grooves or ways between the lugs and the annular band, said connecting member being provided with lugs dovetailed between the annular band and the lugs of the shell.
- 2. In a device of the character described, a shell to contain the compression resisting 40 parts, a draw-bar, and a member connecting

the draw-bar and shell, the latter being provided with external lugs, an annular band, and slots between said band and lugs, the connecting member being provided with lugs engaging within said slots and an annular 45 band encircling the band of the shell.

3. In a device of the character described, a shell adapted to contain a compression resisting means, a draw-bar, and a single piece connecting member for the draw-bar and 50 shell, said member being provided with an annular band at its rear end engageable with the shell and with a box-like head at its front end arranged to receive the draw-bar.

4. In a device of the character described, 55 a shell arranged to contain compression resisting members, a draw-bar, and a member for connecting the draw-bar and shell, the shell being provided with annular grooves on its exterior and said connecting member 60 having lugs arranged to engage in said grooves, said grooves and lugs on the shell and connecting member forming a bayonet joint.

5. In a device of the character described, 65 a shell, a draw-bar, and a member arranged to connect the draw-bar and shell, said shell being provided with lugs and an annular band on the exterior thereof, the lugs and band being spaced apart and thereby forming 70 grooves therebetween, said connecting member being provided with lugs arranged to engage within said grooves, said grooves and lugs forming a bayonet joint connection between said member and shell.

JOHN F. O'CONNOR.
